UNITED STATES PATENT OFFICE.

GILBERT O. HELVIG, OF DAWSON, MINNESOTA.

VALVE-CAP.

1,368,723.

Specification of Letters Patent. Patented Feb. 15, 1921.

Application filed April 23, 1917. Serial No. 163,890.

To all whom it may concern:

Be it known that I, GILBERT O. HELVIG, a citizen of the United States, residing at Dawson, in the county of Lac qui Parle and 5 State of Minnesota, have invented certain new and useful Improvements in Valve-Caps, of which the following is a specification.

My invention relates to improvements in 10 dust caps for the inlet valve tubes of the inner tubes for tires, its object being to provide improved spring means for locking the cap in closing position, thus obviating the necessity of screwing the cap into and out of 15 closing position. To this end my invention consists in the features of construction and combination hereinafter particularly described and claimed.

In the accompanying drawings forming 20 part of this specification—

Figure 1 is an isometric view of part of an auto wheel felly with my improved valve closing cap arranged in connection with a valve tube extending through said felly.

Fig. 2 is a side elevation of a modified form of the invention showing the cap in outline.

Fig. 3 is a view of a spring lock shown in Fig. 1 and forming part of my invention.

Fig. 4 is a detail of the dust cap employed in Fig. 1.

Fig. 5 is a view of a modified form of dust cap, and

Figs. 6 and 7 are details of a nut and 25 spring used in connection with the modified form of cap.

In the drawings A represents the ordinary valve tube of the inner tube 2. The valve tube is locked in position in connection 40 with the wheel felly 3 by the usual interiorly threaded nut 4 intermeshing with the surrounding thread 5 of the valve tube whereby to be screwed down upon the felly as shown.

A washer may be placed over the nut 4. The valve tube contains the usual valve 45 (not shown) the outer end of the tube being closed by the ordinary cap 7.

In carrying out my invention I employ a dust cap B of the usual type except that as 50 shown in Figs. 1 and 4, I form the lower free edge of the cap with an outwardly turned shoulder or rib 8, the cap being of the proper size to slide freely over the tube.

For the purpose of holding the cap shown 55 in Figs. 1 and 4 locked in closing position, I provide a spring member 9, the bottom of the

spring member being positioned between the nut 4 and the felly. The sides of the spring member extend upwardly to form spring fingers 10 to fit over the shoulder 8 of the 60 cap. With the cap locked in closing position as shown in Figs. 1 and 4 an outward pull upon the cap will force the spring fingers apart and allow the cap to be removed.

In placing the cap over the valve tube the 65 shoulder will force the spring fingers apart, the fingers then springing inward over the shoulder to hold the cap in closing position.

In the modified form shown in Figs. 2, 5 to 7, I show a dust cap formed with an interior circumferential rib as shoulder 11. For the purpose of engaging with the shoulder 11 and holding the cap locked in closed position, I provide a plate 12 formed with 70 spring fingers 13 to pass upwardly through 75 slots 14 cut through the threads of the nut 15, the upper ends 16 of the spring fingers being outwardly bent to snap over the shoulder 11 of the dust cap and hold the cap locked in covering position. While I have 80 shown two forms of cap locking spring, I do not restrict myself to these particular forms, but may use other modified constructions working upon the same principle without departing from the idea of my invention. 85

I claim:

1. In a valve stem construction, a pneumatic tire valve tube externally screw threaded, a clamping nut for holding the tube to a wheel felly, a dust cap inclosing the 90 tube and formed on its lower end with a shoulder seating on the nut, and a lock member consisting of a plate perforated to receive the tube and be clamped beneath the nut, and spring fingers carried by the plate 95 for engaging over the shoulder to hold the dust cap seated on the nut.

2. In a valve stem construction, a pneumatic tire valve tube externally screw threaded, a clamping nut for holding the 100 tube to a wheel felly, a dust cap inclosing the tube and formed on its lower end with a shoulder seating on the nut, and a lock member consisting of a plate perforated to receive the tube and be clamped beneath the 105 nut, and spring fingers extending upwardly from the edge of the plate perforation and within the bore of the nut to engage over the shoulder of the dust cap to hold it seated on the nut, said nut having axially extending slots cut through the threads in its bore 110 to receive the fingers of the plate.

3. In a dust cap retainer, the combination with a wheel rim, a valve stem, a lock nut on the stem, and a dust cap, of a dust cap clamping member surrounding the stem and 5 confined against the rim by the lock nut and including spring arms between which the lock nut is disposed, said arms overhanging the nut and adapted to be sprung apart by the cap and to embrace the cap, and inter-

locking parts on the dust cap and spring 10 arms.

In testimony whereof I affix my signature in presence of two witnesses.

GILBERT O. HELVIG.

Witnesses:

H. S. JOHNSON,
GEORGE VOELKER.
